SCRUBBING BRUSH

Filed Feb. 26, 1924

Anton A. Leraas Inventor

By Herbert E. Smith

Attorney

UNITED STATES PATENT OFFICE.

ANTON A. LERAAS, OF SPOKANE, WASHINGTON.

SCRUBBING BRUSH.

Application filed February 26, 1924. Serial No. 695,154.

To all whom it may concern:

Be it known that I, ANTON A. LERAAS, a citizen of the United States, residing at Spokane, in Spokane County and State of Washington, have invented certain new and useful Improvements in Scrubbing Brushes, of which the following is a specification.

My present invention relates to improvements in scrubbing brushes of the fountain type and manually operated, said brushes being especially adapted for use in cleansing carpets, rugs, linoleum or floors. The primary object of the invention is the provision of a hand operated and hand controlled fountain brush by means of which a liquid detergent may be fed by manual control to the brush as required and in which the detergent may be distributed with relation to the brush bristles in such manner as to avoid waste of the detergent and at the same time supply the brush with an ample quantity of the detergent. Means are also provided whereby the detergent distributing parts may be removed and cleansed with facility, and as the brush is constructed it embodies other meritorious features as will be hereinafter more fully pointed out and claimed.

In the accompanying drawings I have illustrated one completed example of the physical embodiment of my invention wherein the parts are combined and arranged in accordance with the best mode I have thus far devised for the practical application of the principles of my invention.

Figure 1 is a perspective view of a brush embodying my invention.

Figure 2 is an enlarged detail sectional view through the tank or reservoir, the brush head, and connections.

Figure 3 is an enlarged detail sectional view of a portion of the brush head showing the distributing pipes and one of the branch supply pipes.

Figure 4 is a detail sectional view of the funnel used to fill the tank or reservoir.

Figure 5 is a longitudinal sectional view of the brush head showing one of the distributing pipes and the branch supply pipes, and a locking means for the former.

In carrying out my invention I utilize that type of brush which is adapted to be reciprocated across the surface to be scrubbed and is utilized by the operator

who stands in upright position. The brush head 1 may be a rectangular block of wood or other suitable material of the desired dimensions and the bristles 2 are secured as usual in sockets in the brush head, and arranged in spaced rows extending longitudinally of the brush head. The brush is manipulated by the long handle 3 which is attached in suitable manner to the brush head, and above the head is carried a reservoir 6 or tank 4 supported on the end brackets 5 that are secured to the head.

The tank is designed to contain the liquid detergent which flows therefrom through the main supply pipe 6 of an inverted T-shape, which pipe is fashioned with a pair of spaced branch supply pipes 7 and 8 extending downwardly therefrom.

In the bottom of the tank an outlet port 10 is provided leading to the supply pipe, and this port is controlled by a conical shaped valve 11 whose stem 12 passes upwardly through the tank and through a stuffing box 13 in the top of the tank.

Normally the valve is held to its seat by means of a coiled spring 14 surrounding the stem and interposed between the stuffing box and a pin 14' fixed to the stem, and the valve is removed from its seat to permit flow of detergent through the valve seat

by manual control. Exterior of the tank I utilize a collar 15 in connection with the stuffing box and the nut 15' clamps the collar rigidly on the stuffing box. A bracket arm 16 is offset from the collar and rises therefrom as a support for a bell crank lever 17, which is pivoted at 18 at the free end of the valve stem which projects through the stuffing box. The short arm of the lever is pivoted at 19 to the rigid bracket arm 16, and a pull cord 20 is attached to the long arm of the lever for actuating the same.

The cord is passed from the lever rearwardly to the handle 3, through guide eyes 21 and is provided with a pull ring 22 in convenient position for access by the operator of the brush. Thus as the brush is manipulated the exit of liquid detergent from the tank to the main supply and branch pipes is controlled by the position of the valve 11, and the valve is opened by a pull on the cord when desired.

The branch supply pipes feed the liquid detergent to two distributing pipes 23 and 24 which are spaced apart and extend longi-

tudinally of the brush head, said pipes being provided with perforations 25 for spraying the liquid detergent.

As seen in Figure 3 each distributing pipe 5 is provided with an upper inlet port 26 with which the branch supply pipe communicates, and at its adjoining end the branch supply pipe is fashioned with an annular flange 27 forming a head for close 10 contact with the distributing pipe and surrounding the inlet port 26.

The distributing pipes are each located in a longitudinally extending groove 28 in the lower face of the brush head, which groove, 15 at one end of the head terminates, as seen in Fig. 5, a short distance therefrom, while at the opposite end the groove opens through the brush head. The grooves are fashioned so that the distributing pipes, one end of 20 which is closed, may be slipped longitudinally into place with the perforated portions of the pipes projecting below the lower face of the brush head, and the closed end of the pipes resting against the projecting 25 portion 28' or shoulder on the brush head.

At their outer ends each distributing pipe is provided with a pair of spaced collars 29 and 30 to form an annular groove therebetween and a knob or handle 31 is attached 30 at the end of the pipe. By means of a locking plate 32 pivoted at one end of the brush head each distributing pipe is retained in position in the head. Said plate is curved to swing around and fit in the groove between the two spaced collars of the pipe, 35 and by these two retaining devices the two pipes are locked in proper position.

Should the spraying orifices 25 become clogged, or if necessary for any other reason to remove the distributing pipes, the pivoted detents 32 may be swung clear of their pipes, then by grasping the handles or knobs 31 the distributing pipes may be pulled longitudinally from the slotted brush 45 head. After cleaning the pipes may again be inserted in position with the inlet ports below the two branch pipes, and the pivoted detents swung to locking position to hold the pipes in place.

50 The tank may be supplied with the liquid detergent through the funnel 33 fixed at the top of the tank, and to prevent splashing

of the detergent through the funnel when the brush is being operated, a baffle plate 34 is fixed in the funnel, openings 35 being provided at the sides of the baffle plate to permit flow of the detergent to the tank while the latter is being filled. 55

As thus constructed the implement is accessible at all parts for cleansing and repair or readjustment of parts. By removing the nut 15' and disconnecting the bell crank lever, and withdrawing the stuffing box, the valve and its stem may be withdrawn from the tank, and the valve seat cleaned, or the 60 whole valve structure including the stem and connections may be withdrawn by unscrewing the stuffing box from the tank. 65

The distributing pipes may be turned slightly on their longitudinal centers to direct the spraying of the liquid detergent, which flows by gravity, with relation to the brushes or bristles in order that the detergent may be uniformly and evenly distributed over the area of the brush in scrubbing or cleansing a surface. 70 75

Having thus fully described my invention what I claim as new and desire to secure by Letters Patent is—

1. The combination with a brush head 80 having a pair of spaced grooves, of perforated, distributing pipes slidably mounted in said groove and having inlet ports, spaced collars on said pipes forming annular grooves, a pivoted detent on said head for engagement with each groove, and means for supplying a liquid detergent to each distributing pipe.

2. The combination with a brush head 90 having a handle, and a pair of spaced grooves on the under side thereof, of perforated removable distributing pipes slidably mounted in said grooves and having inlet ports, means for retaining said pipes in position, a tank supported above the head, a 95 main pipe and a pair of branch supply pipes from the tank communicating with said inlet ports, a valve within the tank for controlling the flow of liquid detergent through the main pipe, and means supported on said handle for controlling said valve. 100

In testimony whereof I affix my signature.

ANTON A. LERAAS.
